UNITED STATES PATENT OFFICE.

JAMES B. BAYNES, OF BUFFALO, NEW YORK.

ENGINE.

Application filed October 28, 1922. Serial No. 597,493.

This invention relates to four-cycle internal combustion engines of the type shown in my prior Patent Number 1,257,447, dated February 26, 1918, and its object is to provide a valve mechanism of great simplicity and which shall conduce to the obtaining of maximum efficiency as well as maximum power of the engine.

This invention consists, in combination with an internal combustion engine cylinder provided with an inlet port adjacent its head and an exhaust port adapted to be opened by the piston at the end of its working and charging strokes, of a cylindrical valve chamber positioned adjacent the cylinder and fitted with a cylindrical valve provided with intake and exhaust passages and with a fuel chamber wherein the major portions of the explosive charges of the engine are compressed.

It also consists in a valve chamber provided with an air compression chamber, an air intake port therefor, a by-pass adapted to connect this air compression chamber with the fuel chamber in the valve and with an exhaust port adapted to connect with this fuel chamber.

It further consists in the details of construction illustrated in the accompanying drawings and particularly pointed out in the claims.

In the drawings, Fig. 1 is a section of this improved engine longitudinally of the cylinder and valve chamber showing the piston and valve at the positions occupied just after the beginning of the charging stroke. Fig. 2 is a similar section showing the parts just after the middle of the compression stroke. Fig. 3 is a similar section just after the beginning of the working stroke. Fig. 4 is a similar section of the engine at the end of the working stroke. Fig. 5 is a similar section showing the parts just after the middle of the scavenging stroke. Figs. 6, 7 and 8 are diagrams of the upper exhaust ports of the valve chamber.

Similar reference characters refer to like parts throughout the several views.

The crank case of this engine comprises the lower part 1 and the upper part 2 which connects to the power cylinder 3 and to the valve chamber 4 which may be integral with the power cylinder if desired. Any other construction of crank case and power cylinder may be used. The power cylinder is formed with an upper or outer port 5 and

with a lower or inner port 6, the former being both an intake and exhaust port, while the latter is merely an exhaust port. Within the cylinder is a piston 7 having a pin 8 on which the connecting rod 9 is mounted, the lower end of the connecting rod engaging the crank pin 10 on the crank 11 of the main shaft 40 of the engine. The cylinder has a head 12 extending into the cylinder and any desired clearance may be had between it and the piston 7, but a minimum clearance is desirable as more thorough scavenging is possible with small clearance.

The valve crank shaft 13 is shown in dotted lines and carries the crank pin 14 to which the valve rod 15 is connected. This shaft is driven in the same or opposite direction as the main shaft at half its speed in any desired manner. The upper end of this valve rod 15 attaches to the pin 19 mounted in the valve which consists of the connected parts 20, 21, 22 and 23. The lead of the valve crank pin 14 is shown to be about 52 degrees relative to the crank pin 10 in Fig. 4, but this lead may be varied as experience dictates.

The valve chamber is formed with an air intake port 16, an upper exhaust port 17, which preferably is divided into separate openings as indicated in Figs. 6, 7 and 8, a lower exhaust port 25, a fuel intake port 24, and with a by-pass 26 in its wall at its upper end for air which is compressed in the upper end of this chamber below the head 27.

The valve is generally cylindrical with a passage 30 for the fuel, a fuel-compression chamber 31 and an exhaust passage 32. While the chamber 31 and passages 30 and 32 are shown to be annular, they may be of any other desired form or proportions. An exhaust pipe 35 is shown connected to the valve chamber over the ports 17. The operation of this engine is as follows.

Operation.

When the parts are in the position shown in Fig. 1 and the engine is in operation, the piston 7 is descending and the valve 20 is at about the upper end of its travel, the passage 30 having connected the cylinder port 5 with the fuel port 24 at about the time the piston began to move down.

As it takes some time for the charge to begin to move into the cylinder, it might be desirable, especially in engines running at high speeds, to pre-open the port, that is,

- connect immediately before the piston begins to move down. Or the timing of the valve and piston may be changed a little so as to open this port immediately before the piston begins to move down and still leave the same sequence of events. The passage 30 is therefore said to connect the cylinder port 5 with the fuel port 24 at about the time the piston begins to move down.
- 10 The cylinder becomes charged with fuel while the valve completes its upward movement and begins to move down, the connection between the ports 5 and 24 continuing until just about the time the piston has reached the end of its charging stroke, at which time there is practically no outward movement of the piston while the valve is moving down at nearly maximum speed. Therefore, before the inertia of the inflowing fuel has been overcome by the filling of the cylinder and the upward movement of the piston 7, the valve has closed the port 5 so that compression of the charge may begin.
- 15 At about the beginning of the compression stroke the valve has moved down sufficiently to connect the fuel chamber 31 with the port 5, and as a result the fuel becomes compressed in this chamber, after which the charge is exploded. The valve begins to move upward just after the beginning of the working stroke and the compression chamber 31 remains connected with the working cylinder during the entire working stroke, shown in Fig. 4, so that the expansion of the ignited fuel in the chamber 31 may have its full effect on the piston 7.
- 20 When the piston is at the lower end of the charging stroke, the exhaust port 6 is covered by the valve, but at the end of the working stroke (Fig. 4) the exhaust ports 6 and 25 register with the exhaust passage 32 in the valve.
- 25 The charge is ignited just after the parts are in the position shown in Fig. 2, depending upon the speed of the engine, and the piston moves down under the pressure of the ignited charge. The valve moves down a short distance and then up until the parts are as shown in Fig. 4, at which time the piston has completed its working stroke and opened the port 6, which permits most of the burnt gases in the cylinder and in the fuel chamber 31 to flow out through the passage 32. The major portion of the burnt gases flows through the ports 6 and 25 and the passage 32 to the atmosphere, but the remaining portion is expelled from the cylinder during the upward stroke of the piston into the fuel chamber 31. The momentum of the burnt gas as it passes out through the port 5, compression chamber and ports 17 is such that but a slight amount is left in the cylinder and in these passages. The removal of substantially all the burnt gases before the admission of the fuel results in practi-

cally pure fuel in the cylinder at the instant of the explosion which insures maximum power, not only because of full volume of the cylinder being utilized but also because of the absence of inert gases which have a tendency to stifle the flame and to cause slow burning of the fuel. This is particularly important in high speed engines where the duration of the working stroke is often only 1/120 of a second. At the end of the scavenging stroke of the piston 7 the part 22 of the valve covers the port 5 of the cylinder 3 and continued movement of the piston connects the fuel passage 32 to this port.

75 During the downward travel of the valve, its upper end causes a partial vacuum in the upper part of the valve chamber. When the valve reaches the lower end of its stroke the part 23 of the valve uncovers the air passage or port 16 so that the chamber above it becomes filled and this air is compressed during the upward movement of the valve. When the parts reach the positions shown in Fig. 1, the air compressed in this chamber escapes into the fuel chamber 31 through the by-passes 26 and forces out what little remaining burnt gases there may be therein through the passages 17.

80 The working cylinder is therefore in connection with the fuel inlet port 24 during the entire charging stroke and is connected with the compression chamber 31 during the compression, working and scavenging strokes. The socket for the spark plug 39 may connect to the compression chamber at 85 the end of the compression and beginning of the working strokes or may be mounted in any other convenient manner. The compression chamber 31 connects to the upper exhaust ports 17 during practically the entire scavenging stroke and during much of the charging stroke, but during the charging stroke this chamber is disconnected from the working cylinder.

85 Instead of a single passage, I prefer a group of ports 17 for the final discharge of the exhaust and these may be arranged in any desired manner, three arrangements shown in Figs. 6, 7 and 8 being examples.

90 It will be observed that the volume of the fuel-compression chamber may be varied by increasing or decreasing the diameter of the connection 23 between the parts 22 and 23 of the valve. Also that the upper air compression chamber 26 or the lower exhaust port 6 and the passages 32 and 25 or both the chamber 26 and the lower exhaust may be omitted, but the efficiency of the engine will be reduced thereby. Engines with these omissions may be constructed at somewhat 95 less expense.

95 The weight of engines constructed according to the accompanying drawings may be considerably less than those of the same horsepower of the present accepted four cy- 100

cle types. The necessity of frequent grinding of poppet valves is entirely absent.

It will be understood that the above description and the drawings referred to represent merely one embodiment of my invention and that the details of construction may all be modified without departing from the spirit of my invention as set forth in the following claims.

10 I claim:

1. In an internal combustion engine, the combination of a cylinder and a piston therein, a valve chamber adjacent to and connected to the cylinder by a plurality of ports, one of which is opened by the piston when at the inner end of its stroke to permit initial exhaust and the other port being at the opposite end of the cylinder, to admit fuel and permit complete exhaust, said 15 valve chamber also having outer and inner exhaust ports and an inlet port between them, and a valve slideable in the chamber and provided with passages to connect the inner port of the cylinder with the inner exhaust port of the valve chamber and to connect the other port of the cylinder with the inlet port and the outer exhaust port of the valve chamber alternately, and with a chamber to receive a portion of the exhaust gases 20 of the engine.

2. In an internal combustion engine, the combination of a cylinder and a piston therein, a valve chamber adjacent to the cylinder and connected to the cylinder by two 25 ports which are respectively at the ends of the working chamber of the cylinder, said valve chamber having a plurality of exhaust ports and a fuel intake port, and a valve slideable in said chamber and having a series 30 of passages, two of the passages being adapted to connect the ports of the engine to the exhaust ports of the valve chamber and a third to connect one of the engine ports to said fuel intake port of the valve chamber.

3. In an internal combustion engine, the combination of a cylinder and a piston therein, a valve chamber adjacent to the cylinder and connected to the cylinder by two ports 50 which are respectively at the ends of the working chamber of the cylinder, said valve chamber having a plurality of exhaust ports and a fuel intake port, and a valve slideable in said chamber and having a series of passages, two of the passages being adapted to connect the ports of the engine to the exhaust ports of the valve chamber and a third to connect one of the engine ports to said fuel intake port of the valve chamber, said 55 valve chamber having an additional port communicating with the atmosphere and a passage in its wall to provide for the complete removal of the burnt gases.

4. In a four-cycle internal combustion engine, the combination of a cylinder having

a port at each end of its working chamber, a valve chamber adjacent the cylinder and connected thereto by said ports and having two exhaust ports and an intake port for fuel, a valve slideable in the chamber and having an exhaust passage, a fuel passage and a chamber to receive the explosive charge of the engine and which acts as an exhaust passage during the scavenging stroke of the engine.

5. In an internal combustion engine, the combination of a cylinder having a port at each end of its working chamber, a piston therein adapted to open said ports, a valve chamber connecting to said cylinder by said ports and having an air compression chamber at one end, an air inlet port for said air compression chamber, two exhaust ports and a fuel intake port, and a valve slideable in the valve chamber having an exhaust passage adapted to connect one of the cylinder ports to one of the exhaust ports of the valve chamber and having a fuel passage adapted to connect the second cylinder port to the fuel intake port of the valve chamber and also having a chamber adapted to connect to said second engine port to receive fuel from the cylinder during the compression stroke of the piston and to remain connected to said port during the working stroke 95 of the piston, said fuel chamber connecting to the second exhaust port of the valve chamber during and after the scavenging stroke of the piston, said valve chamber having a passage to conduct air from the air compression chamber to said fuel chamber in the valve while connected to said second exhaust port.

6. In a four-cycle internal combustion engine, the combination of a cylinder and a piston therein, a valve chamber adjacent thereto and connected to the cylinder by a port at the outer end of the cylinder, and a valve slideable in the chamber and having a passage to connect the port to a source of fuel supply 110 during the charging stroke of the piston and also having a fuel chamber which communicates with said port during the compression, working and scavenging strokes of the piston, said valve having an exhaust port with 115 which said fuel chamber communicates during the scavenging stroke of the piston.

7. In a four-cycle internal combustion engine, the combination of a cylinder and a piston therein, a valve chamber adjacent thereto and connected to the cylinder by a port at the outer end of the cylinder, a valve slideable in the chamber and having a passage to connect the port to a source of fuel supply 120 during the charging stroke of the piston and also having a fuel-compression, chamber which communicates with said port during the compression, working and scavenging strokes, a crank shaft and connecting rod connecting to the piston, a second crank 125

- shaft and connecting rod connecting to the valve, the valve crank shaft rotating at half the speed of the other, said valve having an exhaust port with which said compression chamber communicates during the scavenging stroke, and a spark plug mounted in the wall of the valve chamber in alinement with said compression chamber when the piston is at the end of the compression stroke.
- 10 8. In a four-cycle internal combustion engine, the combination of a cylinder and a piston therein, a valve chamber adjacent thereto and connected to the cylinder by a port at the outer end of the cylinder, a valve slideable in the chamber and having a passage to connect the port to a source of fuel supply during the charging stroke of the piston and also having a fuel-compression chamber which communicates with said port during the compression, working and scavenging strokes, a crank shaft and connecting rod connecting to the piston, a second crank shaft and connecting rod connecting to the valve, the valve crank shaft rotating at half the speed of the other, said valve having an exhaust port with which said compression chamber communicates during the scavenging stroke, and a spark plug mounted in the wall of the valve chamber in alinement with said compression chamber when the piston is at the end of the compression stroke, the outer end of the valve chamber being closed to constitute an air-compression chamber, said valve having a by-pass to permit the air compressed therein to flow into the fuel-compression chamber at the end of the outward movement of the valve and having an air inlet port to communicate with the air-compression chamber when the valve is at the end of its inward movement.

JAMES B. BAYNES.
